UNITED STATES PATENT OFFICE

159,433

SANDING MACHINE OR SIMILAR ARTICLE

Robert E. Nixon, Orange, Mass.

Application April 30, 1949, Serial No. 2,364

Term of patent 14 years

(Cl. D37—1)

To all whom it may concern:

Be it known that I, Robert E. Nixon, a citizen of the United States of America, residing at Orange, in the county of Franklin and Commonwealth of Massachusetts, have invented a new, original, and ornamental Design for a Sanding Machine or Similar Article, of which the following is a specification, reference being had to the accompanying drawings, forming a part thereof.

Fig. 1 is a side elevational view of a sanding machine or similar article showing my new design;

Fig. 2 is a side elevational view of the sanding machine looking at the opposite side from that of Fig. 1;

Fig. 3 is a top plan view of the sanding machine shown in Fig. 1; and

Fig. 4 is an end elevational view of the sanding machine looking from right to left at the machine shown in Fig. 1.

I claim:

The ornamental design for a sanding machine or similar article, substantially as shown.

ROBERT E. NIXON.
